Inventor:
John P. Theofilos,
by Robert Burns,
—
H. H.

UNITED STATES PATENT OFFICE.

JOHN P. THEOFILOS, OF CHICAGO, ILLINOIS.

KINESITHERAPEUTIC APPARATUS.

Application filed November 10, 1922. Serial No. 600,058.

To all whom it may concern:

Be it known that I, JOHN P. THEOFILOS, a citizen of the United States of America, residing at Chicago, in the county of Cook and State of Illinois, have invented certain new and useful Improvements in Kinesitherapeutic Apparatus, of which the following is a specification.

This invention relates to that type of 10 kinesitherapeutic or massage apparatus in which the applicator receives rapid reciprocation in a rectilinear or in a circular path, and the present improvement has for its objects:—

15 To provide a structural formation and combination of parts, whereby rapid reciprocations in reverse directions are imparted to twin applicators of the band type, and which in the varied uses of the apparatus 20 can be changed so that the above mentioned twin bands can be employed as a driving means for imparting a reverse rotary movement to an applicator head.

To provide means for maintaining the 25 twin applicator bands in a required spaced relation and against undue separation or too near approach in continued actual use, all as will hereinafter more fully appear.

In the accompanying drawings:—

30 Fig. 1, is a perspective view illustrating the general arrangement of parts in the preferred form of the invention.

Fig. 2, is a plan view of the same.

Fig. 3, is an enlarged fragmentary plan 35 view of the adjustable tie straps used to prevent undue separation of the twin applicator bands.

Fig. 4, is a detail central section of the 40 twin crank head of the operating motor.

Fig. 5, is a detail perspective view of the 45 rigid stay rod employed to hold the twin applicator bands in proper spaced relation.

Fig. 6, is a perspective view of a modified 50 or primary form of the twin applicator bands.

Figs. 7 and 8, are fragmentary views illustrating different surface formations of an 55 applicator band.

Fig. 9, is a central section on line 9—9, 60 Fig. 10, of a duplex revoluble applicator head adapted for use with the main construction of the invention.

Fig. 10, is a detail side elevation of the same.

Like reference numerals indicate like parts 55 in the several views.

Referring to the drawings, 1, designates an end portion of a rotary motor of any usual and suitable type, the power shaft of which carries at one end a crank head 2 having a pair of crank pins 3 and 4 arranged in diametrically spaced relation as shown in Figs. 1, 2 and 4.

5 designates twin bands of pliable material, attached at one end to the respective 65 crank pins, 3, 4, so as to receive simultaneous reciprocation therefrom in opposite directions, while at their other ends the bands 5 are united together by return bends or loops 6, which in the primary type of the invention shown in Fig. 6, may be a bend or loop formed in a single band or strip of the required length. In the preferred construction however said bend or loop is formed by a separate flexible connection 7, the respec- 70

75 tive ends of which are connected to the end of the bands 5 remote from the connection thereof to the crank pins aforesaid, by intermediate resilient connections 8, preferably of the coiled wire type shown. In such

80 preferred form of the invention, the flexible loop connection 7 has bearing engagement with the periphery of a pulley 9, the carrying housing 10 of which is attached by a flexible cord 11 and clip 12 to a convenient 85 fixed article in the operating room.

For various specific uses, the applicator bands 5, may be made of coarse and hard woven fabric as illustrated in Fig. 8, or the surface of each band may be provided with 90 a plurality of transverse ridges 13 as shown in Fig. 6 or with a serpentine ridge 13' as shown in Fig. 7, to afford the particular massage effect desired.

14 designates a centrally arranged stay of 95 wire or the like, formed with rebent ends 14' adapted to engage in loops 15 of fabric on the bands 5, to hold the same in properly spaced relation in actual use.

16 designates one or more supplementary 100 flexible straps connected to the bands 5 in an adjustable manner, preferably by a button and a series of button holes as shown in Fig. 3, to hold the bands from undue separa-

tion in actual use. In the construction shown the ends of said straps 16 are folded into loops to constitute the loops 15 above mentioned.

5 In the modification shown in Figs. 9 and 10, the band aforesaid is shown as having the form of an open loop, 5', the free ends of which are formed for attachment to the crank pins 3, 4, aforesaid, 10 while the opposite or looped end is adapted for operative engagement in peripheral grooves of a duplex rotary applicator head as follows:—

15 17 and 18 designate twin heads of a cylindrical and substantially counterpart construction, connected together by an axially arranged screw shaft 19, so that either head may have a rotary motion independent of the other head, in order that one head may 20 be held in the hand of the operator as a holder upon which the other head is free to rotate for applicator uses. Each head 17, 18 is formed with a plurality of peripheral 25 grooves, 17' 17'' and 18', 18'' of different diameters and adapted to receive the loop end of the band 5' and receive different speeds of rotation therefrom, as may be required in the various uses of the appliance.

The heads 17 and 18 are adapted to carry 30 different type of applicators best suited to particular treatments. In Figs. 9 and 10, one head 17 is shown as carrying a radially adjustable button type of applicator 20, on its end, while in Fig. 9 the head 18 is shown 35 as carrying a concave applicator 21 on its end, with such applicator preferably formed of rubber or like yielding material.

In practical use of the preferred form of the invention shown in Figs. 1 to 4 inclusive, 40 the pulley 10 is attached by its flexible connection 11 and clip 12 to a fixed object remote from the motor 1, such for instance as the back portion of a barber's chair, and with the person receiving treatment located 45 between said pulley and motor. As so arranged rotation of the power shaft of the motor, will through the opposed cranks 3 and 4 impart rapid and simultaneous reciprocating movements to the twin bands 5 in 50 opposite directions, and with such twin bands in contact with the surface of the person undergoing treatment, a very effective massage effect is attained.

In the use of the twin bands or portions 55 5, unprovided with the pulley 10 and its connections 11 and 12, above described, and as illustrated in Fig. 6, the portion of the person undergoing treatment will form the bearing around which such bands or portions 60 5 has the described reciprocating movement to attain the required massage effect.

In use with applicators 17 and 18, shown in Figs. 9 and 10, the twin bands or portions 5', as a whole or unit, are adapted to engage 65 and impart reciprocating rotary motion to

either one or the other of the applicator heads 17 or 18, with which it may be in driving connection, and with the applicator not in engagement used as a holding handle by the operator. 70

Having thus fully described my invention, what I claim as new and desire to secure by Letters Patent is:—

1. In a kinesitherapeutic apparatus, the combination of a rotary crank head 75 adapted for fixed attachment to the end of the power shaft of a rotary motor and carrying a pair of crank pins in diametrically opposed relation at the end opposite to that formed for attachment to the power shaft, a flexible band having a loop shape the ends of which are operatively connected to said crank pins, and applicator means associated with said band. 80

2. In a kinesitherapeutic apparatus, the combination of a rotary crank head carrying a pair of crank pins in diametrically opposed relation, a flexible applicator band having a loop shape the ends of which are operatively connected to said crank pins, and a pulley connected to the looped end of the applicator band and provided with anchoring means. 85

3. In a kinesitherapeutic apparatus, the combination of a rotary crank head carrying a pair of crank pins in diametrically opposed relation, a pair of applicator bands each connected at one end to the respective crank pins, resilient members connected to the other ends of said bands, a flexible loop 95 member connected to the ends of said resilient members, and a pulley connected to said flexible loop member and provided with anchoring 100 means. 100

4. In a kinesitherapeutic apparatus, the combination of a rotary crank head carrying a pair of crank pins in diametrically opposed relation, a pair of applicator bands each connected at one end to the respective crank pins, resilient members connected to the other ends of said bands, a flexible loop member 110 connected to the ends of said resilient members, and a pulley connected to said flexible loop member and provided with anchoring means, the same comprising a flexible connection and attaching clip. 115

5. In a kinesitherapeutic apparatus, the combination of a rotary crank head carrying a pair of crank pins in diametrically opposed relation, a pair of applicator bands each connected at one end to the respective crank pins, resilient members connected to the other ends of said bands, a flexible loop member connected to the ends of said resilient members, a pulley connected to said flexible loop member and provided with anchoring means, and a transverse stay member attached to the applicator bands to maintain the same in separated relation. 120

6. In a kinesitherapeutic apparatus, the 125

combination of a rotary crank head carrying a pair of crank pins in diametrically opposed relation, a pair of applicator bands each connected at one end to the respective crank pins, resilient members connected to the other ends of said bands, a flexible loop member connected to the ends of said resilient members, a pulley connected to said flexible loop member and provided with anchoring means, and transverse flexible tie straps adjustably attached to the applicator bands to maintain the same against undue separation. 10

Signed at Chicago, Illinois, this 1st day of November, 1922.

JOHN P. THEOFILOS.
